UNITED STATES PATENT OFFICE

RUSSELL F. TUCK, OF LONG BEACH, CALIFORNIA

DERRICK SAFETY APPLIANCE

Application filed April 30, 1928. Serial No. 274,109.

This invention relates to a derrick safety appliance to be used in protecting the derrick man during the drilling, pumping, or repair of an oil well, and to keep him from being 5 injured by falling to the floor of the derrick. The derrick man stands on a board near the top of the derrick and his ordinary duty is to handle the elevators to release or engage the pipe, sucker rods, and so forth, as they 10 are withdrawn or run into the well. It frequently occurs that the derrick man is caught by the hook, elevator or the like, and is jerked upwardly off of the board and then falls off of the hook, down onto the floor of the derrick. 15

An object of my invention is to provide an appliance to which the derrick man is attached whether he is standing on the board, or is carried upwardly by the hook.

20 Another object is to provide an appliance of the character stated in which the shock of the falling derrick man is relieved so that the attaching rope, or encircling belt, will not part and permit the man to fall 25 to the floor.

A further object is to provide an appliance of the character stated which can be readily attached to any usual and well-known type of derrick.

30 Other objects, advantages, and features of invention may appear from the accompanying drawing, the subjoined detailed description, and the appended claims.

In the drawing:

35 Fig. 1 is a fragmentary sectional view of a derrick with my appliance in position therein.

Fig. 2 is a side elevation of my appliance with parts shown in section.

40 Fig. 3 is a transverse sectional view of the rider.

Referring more particularly to the drawing, a pair of brackets 1, 2 are secured to the derrick girders 3, 4 by suitable means, such 45 as the hook bolts 5, 6, or the like. The hook bolts are preferable in event that the derrick is of steel construction but if it is of wood the guides may be nailed or otherwise secured in position. The brackets 1, 2 are 50 spaced a considerable distance apart and a

rod 7 extends between the brackets and is slidably mounted therein. Nuts 8, 9 are screwed to the bottom, respectively, of the rod and a coil spring 10 surrounds the rod and is positioned between the nut 8 and the 55 top of the bracket 1. The purpose of this spring will be further described.

A rider 11 is slidably mounted on the rod 7 and is provided with an opening 12 therethrough, the side walls of which are inclined, 60 as shown at 13, 13, so that top and bottom sharp edges are pressed to the rod for the purpose of holding the rider in position on the rod. Obviously, if the outer edge of the rider is tilted upwardly the inclined surfaces 65 13, 13 will permit free movement upwardly along the rod. An opening 14 is provided through the rider in which the rope, or preferably a wire cable, is secured which leads to the belt around the waist of the derrick 70 man.

A spring 15 is provided for the purpose of holding the rider in a position to always engage the rod so that it will not readily slide down along the rod, and one end of this 75 spring is secured to the rider and the other end extends upwardly and partly encircles the rod, thus pressing the outer end of the rider downwardly and tending to bring the sharp edges of the opening 12 into engagement with the rod. Thus the rider will always be held and will not readily fall downwardly along the rod. An adjustable stop collar 16 is provided on the rod for the purpose of limiting the downward movement 80 of the rider.

In operation, if the derrick man should be caught by the hook and carried upwardly the rider will follow along the post and when the derrick man falls off of the hook, either by disengaging himself or by his clothes tearing, he will fall only a short distance. In fact, just the length of the connecting cable between his belt and the rider and then his 95 further fall will be stopped. The rod 7 will yield against the spring 10, thus overcoming the shock of the fall. If the rider 11 should slide downwardly along the rod the stop collar 16, which is always positioned 100

above the bracket 2, will catch the same and the post will yield, as above described.

In order that the driller on the floor of the derrick may be made aware of an accident to the derrick man, I provide a cable 17 which is secured to the rider 11, and this cable extends over sheaves 18 secured to the derrick. A suitable signaling device (not shown) is provided on the floor of the derrick and the cable 17 extends thereto; thus when the rider 11 is carried upwardly or downwardly, the cable 17 will be bolted to actuate the signal device, thus apprising the driller of the fact that an accident has occurred. 15 The driller then stops the hook or elevator and the derrick man is released.

Having described my invention, I claim:

1. A safety derrick appliance comprising a post, means slidably mounting said post on the derrick, yieldable means against which

20 said post rests, and a rider slidably mounted on the post to which the derrick man is secured, and means on the rider adapted to grip said post.

25 2. A safety derrick appliance comprising a pair of brackets, means securing said brackets to the derrick, a post slidably mounted in said brackets, spring means against which said post rests, and a rider slidably mounted on the post to which the derrick man is adapted to be secured, and means on the rider adapted to grip said post.

30 3. A safety derrick appliance comprising a pair of brackets, means securing said brackets to the derrick, a post slidably mounted in said brackets, spring means against which said post rests, and a rider slidably mounted on the post to which the derrick man is adapted to be secured, and a stop collar secured to said post above the lower-most bracket.

35 4. A safety derrick appliance comprising a pair of brackets, means securing said brackets to the derrick, a post slidably mounted in said brackets, a nut screwed onto the top and bottom of said post, a spring between the top nut and the upper bracket whereby the post is yieldably mounted, and a rider slidably mounted on the post between the brackets to which the derrick man is adapted to be secured and means on the rider adapted to grip said post.

50 5. A safety derrick appliance comprising a pair of brackets, means securing said brackets to the derrick, a post slidably mounted in said brackets, a nut screwed onto the top and bottom of said post, a spring between the top nut and the upper bracket whereby the post is yieldably mounted, and a rider slidably mounted on the post between the brackets to which the derrick man is adapted to be secured, and a spring engaging said rider adapted to hold the same in any position on the post.

55 6. A safety derrick appliance comprising

a pair of brackets, means securing said brackets to the derrick, a post slidably mounted in said brackets, spring means against which said post rests, and a rider slidably mounted on the post to which the derrick man is adapted to be secured, and a spring engaging said rider adapted to hold the same in any position on the post.

70

7. A safety derrick appliance comprising a pair of brackets, means securing said brackets to the derrick, a post slidably mounted in said brackets, spring means against which said post rests, and a rider slidably mounted on the post to which the derrick man is adapted to be secured, and a spring engaging said rider adapted to hold the same in any position on the post, and a stop collar adjustably secured to the post above the lowermost bracket.

75

8. A derrick safety appliance comprising upper and lower brackets, means securing said brackets to the derrick, a post slidably mounted in the brackets, a nut screwed onto the top and bottom of the rod, a coil spring surrounding the rod and positioned between the upper nut and the upper bracket, a rider slidably mounted on the rod between the brackets, said rider having an elongated opening therein to permit free movement upwardly along the rod, and a spring secured to the rider and engaging the rod whereby the rider is held at any point along the rod, and a stop collar on the rod above the lower-most bracket.

85

9. In testimony whereof, I affix my signature.

RUSSELL F. TUCK.
